RESCUE TANK

Hugo E. Grieshaber, New London, Conn., assignor to Electric Boat Company, Groton, Conn., a corporation of New Jersey

Application September 18, 1930
Serial No. 482,671

11 Claims. (Cl. 114—16.7)

This invention relates to rescue devices for use with submarine boats, and more particularly to what I term a rescue tank and associated parts for effecting rescue of the personnel of a disabled and submerged submarine boat.

It is known to provide submarine boats with access hatches through which the personnel may escape when the boat is disabled and submerged in shallow water. This manner of escape is not possible, however, at appreciable depths, due to the great pressures obtaining at depths of a hundred feet or more.

One of the main objects of my invention is to provide simple and efficient means whereby the personnel of a disabled and submerged submarine boat can be rescued with a minimum of delay and without being subjected to the pressure of the water in which the boat is submerged. A further object is to provide a buoy and means associated therewith for securing the buoy to the submarine boat by a cable, the buoy being released and serving to mark the position of the boat when it reaches the surface. Another object is to provide a rescue tank having means co-acting with the cable for properly positioning the tank upon the hatch trunk of the disabled boat, the tank also having associated therewith means for guiding the tank into position upon the boat trunk, this guiding means being removable to permit of ready access to the tank from the boat. Further objects and advantages of my invention will appear from the detailed description.

In the drawings:—

Figure 1 is a sectional view through an access hatch trunk and associated parts of a submarine boat and through a rescue tank in accordance with my invention seated upon the trunk;

Figure 2 is a sectional view through the access hatch trunk of the boat and associated parts, showing the buoy in position within the trunk;

Figure 3 is a detail, partly in section, of the means for operating the cable winding drum from within the tank;

Figure 4 is a sectional view through the boat hatch trunk and associated parts, showing the normal positions of the hatch trunk covers;

Figure 5 is a semi-diagrammatic view illustrating the operation of drawing the tank downwardly onto the boat hatch trunk.

My invention is intended for use with a submarine boat comprising a hull 1, a superstructure 2, and an access hatch trunk 3 extending through the upper portion of the hull. The upper end of this trunk is provided with a cover 4 for closing the same, this cover being hinged at 5 and pro-

vided with an arm 6. A toggle 7 is hinged at one end to arm 6, the joint of this toggle being connected by a link 8 to the upper end of a rod 9 extendable through a stuffing box 10 extending through hull 1. A hand wheel 11 is suitably secured to the lower end of rod 9 within hull 1, for imparting endwise movement to the rod in either direction. By pulling the rod downwardly, cover 4 is swung about its hinge 5 into open position.

The cover 4 has associated therewith locking gear 12 of known type for securing the cover closed. A gasket 13 is suitably mounted in the underface of cover 4 and seats upon the coaming at the upper end of trunk 3 to form a water tight closure therewith, when the cover is in closed position. The locking gear 12 is detachably secured, in a suitable manner, to a clevis member 14 suitably secured in cover 4. Normally, the locking gear remains in position attached to clevis member 14 but, when it is desired to utilize the marker buoy, the locking gear is detached from the clevis member and removed from within the trunk 3, as will be later explained.

The inner or lower end of trunk 3 is provided with a main cover 15 hinged to the trunk at 16 (Fig. 4). This main cover 15, when closed, is secured in closed position by swing bolts 17 or in any other suitable manner. A gasket 18 is suitably mounted in the upper face of cover 15 and seats upon the coaming at the lower end of the trunk to form a water tight closure therewith. The main cover 15 is provided with an opening therethrough forming a manhole 19. This manhole is normally closed by a manhole cover 20 hinged at 21 to cover 15. A hook bolt 22 passes through manhole cover 20 and engages beneath the adjacent portion of cover 15 for securing cover 20 in closed position. A nut 23 screws upon the upper end of bolt 22 and bears against the collar 24 of an indicating and locking device 25 through which the bolt 22 passes, collar 24 being suitably connected to the bolt, in a known manner, to prevent relative turning movement between this collar and the bolt. Normally, nut 23 is turned tightly onto bolt 22 so as to hold manhole cover 20 in closed position. A gasket 26 is suitably mounted in the upper face of cover 15, adjacent manhole 19, and the peripheral portion of manhole cover 20 seats upon this gasket so as to form a water tight closure therewith.

Manhole cover 20 is provided on the upper face thereof, at a point coincident with the axis of hatch trunk 3, with an eye member 27. A cable 28 is coiled upon the covers 15 and 20, one end of 110

this cable being provided with a shackle 29 which is suitably secured, as by a pin 30, to eye member 27. An eye 31 is secured upon the other end of cable 28 and is adapted to be detachably secured 5 in a suitable manner, as by means of a pin 32, to a shackle 33 suitably secured to a buoy 34 of a size and shape to fit into the trunk 3. This buoy is provided, at the lower portion thereof, with suitably disposed brackets 35 in which are 10 mounted dogs 36, these dogs being urged outwardly in a known manner toward the surrounding wall of the trunk. A ring 37 is suitably secured in the trunk and, when the buoy 34 is in position in the upper portion of the trunk, the 15 dogs 36 rest upon this ring and hold the buoy against downward movement. As above noted, before inserting the buoy into the trunk, the locking gear for the door 4 is removed.

Normally, the buoy 34 is removed from the 20 trunk and is suitably stowed within hull 1, and the lower trunk cover 15 is held in open position by suitable tackle 38, in a known manner and as shown in Fig. 4. The trunk 3, is, therefore, normally unobstructed and, when the boat is on 25 the surface, gives ingress to and egress from the hull 1. When the boat is submerged, the cover 4 is secured in closed position by the locking gear 12. The cable 28 is held in position upon the covers 15 and 20 by lashings comprising a suitable rope 39 which passes over and about the coiled cable and is inserted through eyes 40 and 41 suitably disposed about covers 15 and 20, respectively. Lashing the cable in this manner 30 serves to effectively prevent uncoiling or disarrangement thereof, thus maintaining the cable in proper position upon the covers while permitting closing and opening of cover 15 as conditions may require. In case the boat is disabled and submerged, locking gear 12 is first detached from clevis 14 and is removed from the 35 trunk 3. Eye 31 of the cable 28 is then secured to shackle 33 of buoy 34, and the buoy is then positioned within the upper portion of trunk 3 as in Fig. 2. Cover 15 is then moved into closed 40 position and, as it approaches this position, the lashing rope 39 is cut at suitable points and to such an extent that the uncut threads of this rope will readily break when subjected to slight tension. The cover 15 is then completely closed and 45 is secured tightly in this position by means of the swing bolts 17. Water is then admitted to trunk 50 3 from the sea so as to equalize the pressures at the opposite sides of cover 4, this cover being then opened so as to permit the buoy 34 to leave the trunk. This buoy has sufficient buoyancy to break 55 the uncut threads of the lashing 39, by the pull exerted upon cable 28, and to rise to the surface with the attached cable.

For flooding the trunk 3, I provide a flood pipe 60 42 open to the sea at one end, the other end of this pipe opening into the trunk. This flood pipe is controlled by a valve 43 disposed within hull 1, this valve being normally closed. I also preferably provide a drain pipe 44 leading from trunk 65 3, adjacent the lower end thereof, this pipe being controlled by a valve operated by a hand wheel 45 suitably secured upon the valve stem 46. This provides means for draining water from the trunk into the boat. After buoy 34 is positioned within 70 trunk 3, valve 43 is opened, admitting water from the sea to the trunk, the valve in the drain pipe 44 being closed at this time. When the pressures at the opposite sides of cover 4 are equalized, this cover is opened and the buoy 34 rises 75 to the surface, as previously stated.

The buoy and cable and associated parts co-operate with a rescue device, in the form of a tank, for rescuing the personnel of the disabled boat. This tank is illustrated in Fig. 1. The tank comprises a body portion 47 and top and bottom heads 48 and 49, welded or otherwise suitably secured to the body portion. An access hatch trunk 50 is suitably secured to head 48, the upper end of this trunk being normally closed by a cover 51 hinged to the trunk at 52 and provided with a securing dog 53. A hatch trunk 54 is suitably secured to head 49 and extends upwardly through this head to a considerable distance, this trunk being disposed centrally of head 49. Trunk 54 is provided with a projection 55 forming, with the adjacent walls of head 49 and ballast tank 56 which extends about the interior of this head, a drum casing. A winding drum 57 is disposed within this casing, this drum being keyed upon a shaft 58 rotatably mounted, at one end, in a bearing sleeve 59 suitably secured to one side wall 55a of the drum casing. The other end portion of shaft 58 is rotatably mounted through a combined stuffing box and bearing structure 60 suitably secured through the other 100 side wall 55b of the drum casing. A worm wheel 61 is secured upon the end of shaft 58 which projects into the tank. This worm wheel meshes with a worm 62 secured upon the lower end of a shaft 63 rotatably mounted in brackets 64 105 suitably secured to wall 55b. The upper portion of shaft 63 is rotatably mounted through a support 65 suitably secured to one of two angle brackets 66 secured to the body 47 of the tank. A bevel gear 67 is secured upon the upper end 110 of shaft 63 and meshes with a bevel gear 68 secured upon a drive shaft 69 rotatably supported, in a suitable manner, by the brackets 66. A hand wheel 70 is secured upon shaft 69 for rotating it. This provides means operable 115 from within the tank for rotating the drum in either direction desired.

A cover 71 is provided for closing the upper 120 end of trunk 54. This cover is hinged, at 72, to the trunk and suitable means, such as swing bolts 73, is provided for securing the cover tightly closed. A gasket 74 is suitably mounted in the underface of cover 71 and is disposed to seat upon the upper end of trunk 54, when the cover is closed, to form a water tight closure therewith. 125

Cover 71 is provided with a depending supporting structure 75 to which is bolted, or otherwise suitably secured, a bracket 76. A yoke 77 is suitably mounted in this bracket, as by means of ball bearings, to turn on an axis coincident 130 with the axis of trunk 54. This yoke is provided, at its lower end, with a bell shaped guide element 78 for guiding cable 28 during winding thereof onto and off of the drum. A guide sheave 79 is mounted in yoke 77, on a horizontal axis, this 135 sheave being disposed to guide the cable in the travel thereof to and from the drum, the central line of the portion of the cable which passes downwardly from the sheave within yoke 77 being coincident with the axis on which the yoke 140 turns. The yoke 77 provides a swinging mounting for the sheave which assures proper delivery of the cable to and from the drum.

A cone shaped guide structure 80 is provided at the lower end of trunk 54. This structure 145 includes a base section 81 having a shoulder 82 contacting the lower face of a flange 83 which projects inwardly from the lower end of trunk 54. A ring 84 is suitably secured, as by cap screws 85, to the upper end of base section 81 150

- and cooperates with shoulder 82 for clamping this section to flange 83 of the trunk. A body section 86 extends downwardly from base section 81 and forms a continuation thereof, the outer face 5 of the body section being flush with the outer face of the base section. This body section is provided at its upper end, with a collar 87, which fits snugly through a corresponding opening in the base section and is provided, at its upper end, 10 with a flange 88 extending over a shoulder 89 of section 81. Securing dogs 90 are suitably mounted upon collar 87 and engage beneath lugs 91 of base section 81 for securing body 86 to the base section. Arms 92 extend inwardly from collar 87, radially thereof, and support a guide ring 93 disposed centrally of the collar for reception of the cable 28. A guide element 94 is suitably secured, as by welding, to the lower end of body 86 and constitutes the tip of the cone structure. 15 This guide element is provided with a downwardly tapering opening for reception of cable 28. The base section 81 and the body 86 and tip 94 constitute a cone guide structure, the outer face of which is smooth and free of obstruction, this structure being particularly adapted to guide the trunk into centered relation to the trunk 3 of the boat. It is particularly pointed out that the exterior diameter of collar 87, taken through flange 88 thereof, is somewhat less than the 20 minimum interior diameter of the upper end of base section 81. By turning the dogs 90 into position to release the body section from the base section, this body section can be raised upwardly through the base section into trunk 54 and, the cover 71 being open and the cable sufficiently slackened, the body 86 and the tip 94 carried thereby, can be disposed within the tank, thus leaving an unobstructed passage from the interior of hull 1 into the tank. 25 An air flask 95 is suitably mounted in the tank and is connected to an air pipe 96 opening, at its lower end, into ballast tank 56, at the top thereof, the upper end of this pipe opening through head 48 of the tank and being adapted for connection, in a suitable manner, to an air hose to a rescue ship for supplying air under pressure to the pipe. This pipe is provided with valves 97 and 98 disposed respectively above and below the connection between pipe 96 and the air flask. Normally, valve 97 is closed, the air from flask 95 being sufficient for ordinary rescue operations. The connection between this flask and pipe 96 is controlled by valves 99 and 100 disposed respectively above and below a connection 30 101 to an air pipe 102 which opens into trunk 54 adjacent the top thereof. This pipe 102 is controlled by a valve 103. A vent pipe 104 opens into the tank from the top of ballast tank 56, this vent pipe being controlled by a valve 105. A gate valve 106 is provided for venting the upper 35 portion of trunk 54 into the tank. A connection 107 is provided between the ballast tank 56, at the bottom thereof, and a passage 108 formed in the wall of trunk 54 and extended to within a short distance of the lower end of this trunk. The connection 107 includes a sea valve 109 and control valves 110 disposed at opposite sides of the valve 109. Normally, all of the valves are closed. 40 In the use of the apparatus, the buoy is released from the disabled boat and rises to the surface, in the manner previously described. The tank may be either towed or lowered from a rescue ship into the water adjacent the buoy, cover 71 of trunk 54 being closed and the cone shaped 45 guide structure being secured in position. The cable is then detached from the buoy and is secured to the drum in a suitable manner, as by means of a short length of cable permanently secured to the drum and passed over the sheave 79 and downwardly through the guide elements 78 and 94. The operating crew then enter the tank through hatch trunk 50, after which the cover 50 51 is tightly secured closed. The cable is then wound onto the drum so as to draw the tank 55 downwardly onto trunk 3 of the boat. The position of the tank as it approaches the boat is illustrated in Fig. 5. Before winding the cable onto the drum, water may be admitted to the ballast tank 56 for reducing the positive buoyancy of the tank to the desired extent. As the tank is pulled downwardly into proximity to trunk 3 of the boat, the cone shaped guide structure enters this trunk and serves to center the tank relative thereto so that a gasket 111 suitably mounted in the lower end of trunk 54 seats upon the upper end of trunk 3 and forms a water tight closure therewith, when the air trapped in the upper portion of trunk 54 is vented by opening valve 106. The tank is then held firmly seated upon the trunk of the boat by 60 the preponderance of pressure exerted upon head 48 and cover 51. The water is then blown out of trunk 54 into ballast tank 56, the ballast tank being at this time vented by means of the vent pipe 104 and the valve 105. For blowing the water out of the trunk 54 but comparatively low pressure is required. Cover 71 is then released and is swung upwardly and inwardly within the rescue tank into position to leave an unobstructed 65 passage through the upper end of trunk 54, the bracket 76 and associated parts moving upwardly out of the trunk in the movement of the cover. To permit of this movement of the cover, the cable drum is rotated in unwinding direction so as to provide sufficient slack in the cable 28 to 70 permit of opening of the cover 71. After cover 71 has been opened, the dogs for securing the body section 86 of the cone structure, one of which dogs is shown at 90, are turned into position to release body section 86 and this section 75 is then moved upwardly through trunk 54 into the rescue tank and disposed therein in position to avoid obstructing the trunk 54. Preferably, before removing the body section 86 of the cone, the water in the boat hatch trunk 3 and the lower 80 end of tank trunk 54, is removed in a suitable manner, as by draining trunk 3 through the drain pipe 44. After draining the trunk 3 and removal of body section 86 of the cone structure, nut 23 on the hook bolt 22 is loosened and this bolt is 85 turned into position to release the manhole cover 20, which is then swung into open position. This gives access from the interior of the hull of the boat to the rescue tank, the men passing from the boat, by means of a suitable ladder, into trunk 90 90 95 100 105 110 115 120 125 130 135 140 145 150 3 and then through trunk 54 into the tank. After the men have entered the tank from the boat, manhole cover 20 is closed and the bolt 22 is turned into securing position, after which nut 23 is turned tightly onto this bolt. Body section 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 means. When the tank reaches the surface, cover 51 is opened and the men escape through trunk 50, by means of a ladder 112. This ladder is connected at its upper end, by pin and slot 5 connections 113, to a bracket 114 secured to head 48 of the tank. When the ladder is in use, it rests upon cover 71, which is then closed as in Fig. 1. When it is desired to open the cover 71, ladder 112 is raised and is swung into position to 10 avoid interference with opening and closing of the cover. The rescue tank is of proper strength to withstand the high pressures which obtain at great depths.

What I claim is:—

15. 1. In combination with a submarine boat, an access hatch trunk extending through the hull, removable covers for the ends of the trunk, means for opening the outer cover from within the hull, a rescue device in the form of a tank having a trunk opening through its bottom and adapted for seating upon the outer end of the boat trunk, a guiding member extending from the lower end of the tank trunk and adapted to enter the boat trunk and center said tank trunk relative thereto, said guiding member being adapted to receive and guide a cable passing therethrough, cable winding means carried by and operable from within the tank, and means for attaching to the lower cover of the boat trunk one end of a cable windable onto and off of said winding means.
20. 2. In combination with a submarine boat, an access hatch trunk extending through the hull, removable covers for the ends of the trunk, means for opening the outer cover from within the hull, a rescue device in the form of a tank provided with a trunk opening through its bottom and adapted to seat upon the outer end of the boat trunk, cable winding and guiding means carried by and operable from within the tank, and means for attaching a cable to the upper side of the inner cover of the boat trunk.
25. 3. In combination with a submarine boat, an access hatch trunk extending through the hull, removable covers for the ends of the trunk, means for opening the outer cover from within the hull, a rescue device in the form of a tank provided with a trunk opening through its bottom and adapted to seat upon the outer end of the boat trunk, cable winding and guiding means carried by and operable from within the tank, a downwardly tapering guiding and centering structure depending from the lower end of the tank trunk and concentric therewith, said structure being adapted to enter the boat trunk and center the tank trunk relative thereto, the guiding structure having a cable receiving and guiding element at its lower end, said structure including a detachable body section movable through the tank trunk into the tank, and means for attaching a cable to the upper side of the inner cover of the boat trunk.
30. 4. In combination with a submarine boat, an access hatch trunk extending through the hull, removable covers for the ends of the trunk, means for opening the outer cover from within the hull, a rescue device in the form of a tank provided with a trunk opening through its bottom and adapted to seat upon the outer end of the boat trunk, a removable cover for the upper end of the tank trunk, cable guiding means carried by the tank trunk cover and arranged to dispose the downwardly extending run of a cable coaxially with said tank trunk, a guiding and centering structure tapering downwardly from the tank trunk and concentric therewith, said structure including a detachable body section provided at its lower end with a cable receiving and guiding element coaxial with the tank trunk, said body section when detached being movable through the tank trunk into the tank, means for attaching a cable to the inner cover of the boat trunk, cable winding means carried by and operable from within the tank, and means for flooding and venting the tank trunk.
35. 5. In combination with a submarine boat, an access hatch trunk extending through the hull, removable covers for the ends of the trunk, means for opening the outer cover from within the hull, a rescue device in the form of a tank provided with a trunk opening through its bottom and adapted to seat upon the outer end of the boat trunk, a removable cover for the upper end of the tank trunk, cable guiding means carried by and operable from within the tank, and means for flooding and venting the tank trunk, and means for flooding and venting the boat trunk.
40. 6. In a rescue device for use with a disabled and submerged submarine boat, a tank provided with a trunk opening through its bottom, a removable cover for the upper end of the trunk, cable guiding means carried by the cover and movable into and out of the trunk in the closing and opening of the cover, a guiding and centering structure tapering downwardly from the lower end of the trunk and concentric therewith, said structure including a detachable body section provided at its lower end with a cable receiving and guiding element, said body section when detached being movable through the trunk into the tank, cable winding means carried by and operable from within the tank, and means for flooding and venting the trunk.
45. 7. In a rescue device for use with a disabled and submerged submarine boat, a tank, a member defining an opening through the bottom of the tank and adapted for cooperation with an access hatch structure of a submarine boat, and a guiding and centering structure tapering downwardly from said member and concentric therewith, said structure including a detachable body section provided at its lower end with a cable receiving and guiding element, said section when detached being movable through said member into the tank.
50. 8. In a rescue device for use with a disabled and submerged submarine boat, a tank, a member defining an opening through the bottom of the tank and adapted for cooperation with an access hatch structure of a submarine boat, and a guiding and centering structure tapering downwardly from said member and concentric therewith, said structure including a detachable body section provided at its lower end with a cable receiving and guiding element, said section when detached being movable through said member into the tank, and cable guiding and winding means carried by and operable from within the tank.

9. In a rescue device for use with a disabled and submerged submarine boat, a tank having a trunk opening through its bottom and adapted for cooperation with an access hatch structure of a submarine boat, a guiding and centering structure tapering downwardly from the lower end of the trunk and concentric therewith, said structure including a detachable body section provided at its lower end with a cable receiving and guiding element, said section when detached being movable through the trunk into the tank, a removable cover for the upper end of the trunk, cable guiding means carried by the cover and movable into and out of the trunk in the closing and opening of the cover, and cable winding means carried by the tank. 80
10. In a rescue device for use with a disabled and submerged submarine boat, a tank having a trunk opening through its bottom and adapted for cooperation with an access hatch structure of a submarine boat, a guiding and centering structure tapering downwardly from the lower end of the trunk and concentric therewith, said structure including a detachable body section 85

- provided at its lower end with a cable receiving and guiding element, said section when detached being movable through the trunk into the tank, a removable cover for the upper end of the trunk, cable guiding means carried by the cover and movable into and out of the trunk in the closing and opening of the cover, and cable winding means carried by the tank, and means for flooding and venting said trunk. 90
11. In combination with a submarine boat, an access hatch structure including a trunk and a removable closure for the outer end thereof, a rescue device in the form of a tank having a trunk opening through its bottom and adapted to seat upon the boat hatch structure and to form a water tight closure therewith, cable winding means carried by and operable from within the tank, a cable windable onto and off of said winding means and passing through said trunk opening centrally thereof, and means for attaching one end of the cable to the boat hatch structure centrally thereof. 95
